Patented Feb. 25, 1969

213,373

TAPE RECORDER CARTRIDGE PLAYER OR THE LIKE

Richard Samuel Cox, Batavia, N.Y., assignor to Sylvania
Electric Products Inc., a corporation of Delaware

Filed July 24, 1967, Ser. No. 7,951

Term of patent 14 years

U.S. Cl. D26—14
Int. Cl. D14—01

Fig. 2

Fig. 3

FIG. 4

FIG. 1 is a front elevational view of a tape recorder cartridge player or the like illustrating my new design;

FIG. 2 is a side elevational view thereof;

FIG. 3 is a top plan view thereof; and

FIG. 4 is a perspective view thereof.

The dominant features of my design are shown in the solid lines.

The back of the article is substantially similar to the front but omitting the slot.

I claim:

The ornamental design for a tape recorder cartridge player or the like, as shown and described.
